DESCRIPTION

U.S. PATENT DOCUMENTS

FIG. 1 is a perspective view of the portable hydraulic spreader device;

4,842,249 A * 6/1989 Weigand ..... 254/93 R
5,272,811 A * 12/1993 Armand 30/228
5,457,889 A * 10/1995 Kimura 30/228
5,956,992 A * 9/1999 Patton 72/392
6,000,680 A * 12/1999 Kimura et al. ..... 254/93 R
6,092,290 A * 7/2000 Vogelsanger 30/228
6,178,643 B1 * 1/2001 Erbrick et al. 30/228
6,244,568 B1 * 6/2001 Patton ..... 254/93 R

FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
